ROLL PAPER RETAINER

Filed Nov. 7, 1928

UNITED STATES PATENT OFFICE

WALLACE D. WHITE, OF NASHUA, NEW HAMPSHIRE, ASSIGNOR TO NATIONAL BREAD WRAPPING MACHINE COMPANY, OF BOSTON, MASSACHUSETTS, A CORPORATION OF MASSACHUSETTS

ROLL-PAPER RETAINER

Application filed November 7, 1928. Serial No. 317,849.

This invention relates to machines for cutting webs of paper into sections, and has particular reference to that type of machine which intermittently draws a web from a supply roll and pushes it to position where a knife cuts it transversely.

In machines of the type shown in Letters Patent No. 1,253,636, granted January 15, 1918, to Sevigne & Arnold, paper to form bread wrapper sections is intermittently fed from a supply roll, over a bed, to position to be cut. In such machines a presser foot bears intermittently on the paper and holds it stationary on the bed while the knife is raised, so that when the next feed of the paper occurs an exact predetermined length will be cut off. It has been found that such presser sometimes causes the paper to stick to the bed, resulting in some interference with starting the paper along for the next step of the feed. To overcome the objection just mentioned, the paper detent or retainer illustrated in Letters Patent No. 1,597,547, granted August 24, 1926, to Sevigne & Chabot was provided. It has been found however, that the pivoted cam-shaped detent or retainer of the last-mentioned patent is liable to affect the wax coating and printing borne by the paper, owing to the wiping action when the paper is drawn under it; also that said detent wears flat in use, and that it is liable to have its effectiveness reduced by becoming more or less coated with the wax of the wrapping paper.

The object of the present invention is to provide improved means located to automatically act on the paper before it reaches the feeding means, to prevent retrograde movement of the paper, and to effect this result without having any wiping action on the paper, thereby avoiding all of the above noted objections.

With the described object in view, the invention consists in the construction and combination of parts substantially as hereinafter described and claimed.

Of the accompanying drawings which illustrate so much of a paper feeding and cutting machine of the type above referred

to as is necessary to an understanding of the present invention:—

Figure 1 is a sectional side elevation of the essential parts of the machine.

Figures 2 and 3 are larger-scale elevations, looking in opposite directions, of the gripping roll and its supporting member.

Figure 4 is a view looking in the direction of the arrow 4 (Fig. 2) and indicating by dotted lines a position which the gripping roll may temporarily occupy when a web of paper is being threaded to position in the machine.

Similar reference characters designate similar parts in all of the views.

A portion of the frame of the machine is illustrated at 40, said frame supporting the shaft 66 of the drum 83. Said drum and a roll or rolls 87 carried by a shaft 89 intermittently push or feed the web of paper over a bed 88 which is transversely slotted for the passage of a knife 129 which is raised and lowered by any suitable means such as suitable connections with arms 132 of a rock shaft 133.

Assuming that the intermittent feeding of the web is effected by intermittently raising the roll or rolls 87 so there will be no cooperation with the drum 83, as explained in the Patent No. 1,253,636 referred to, the paper would then be liable to be then pulled back by the tension devices such as the gravity rolls 84, 85, mounted in the inclined ways 86.

The numerals employed herein are the same as those which designate parts having similar numerals in the Patent 1,253,636 to which reference may be had if further explanation of the said parts and their operation is desired. Letters of reference are employed to designate the parts which cooperate with those having numerals, in attaining the object of the present invention.

To prevent backward movement of the paper web, said web is held or gripped against backward movement while on its way to the feeding members 83, 87. The web of paper from a roll supported by a core 82, after passing under the gravity rolls 84, 85, passes over the drum 83 and under the roll or rolls 87

carried by the shaft 89, and the present gripping action is effected on the middle-width portion of the web on the drum 83.

Supported by the frame 40 is a cross bar 5 a to which the upper portion *b* of a depending bracket is secured, as by screws. The lower portion of the bracket has a flat face providing a plate *c* which is offset from the upper portion, leaving an intermediate shoulder *d*. Projecting rearwardly from the lower portion is a horizontal round stud *e*.

A loosely mounted yoke comprises a cross bar *f*, preferably round in cross section, having arms *g* in which is mounted the axle or 15 shaft pin *h* of a roll *i*, the latter of friction material such as rubber. Normally the yoke and its roll hang loosely from the stud *e*, with the roll resting against the plate *c*, as illustrated by Figure 1.

20 As explained in the Patent No. 1,253,636, the roll 87 and drum 83 are constantly driven in the direction of the arrows, Figure 1, and when the roll 87 is lowered and feeding is effected, one or both of the gravity rolls 84.

25 85, is lifted, and then, when the gravity rolls slide back down, they draw paper from the roll on the core 82, the friction roll *i* preventing the paper from being drawn back by the action of the gravity rolls. Said roll *i* per-

30 mits the web to be readily drawn along for feeding a correct distance, but when the upper roll or rolls 87 rise from the drum 83, the roll *i* automatically grips the paper thereby ensuring accuracy of the lengths of paper to be cut off by the knife 129. This gripping action is due to the converging relationship between the flat plate *c* of the bracket and the surface of the drum 83, and the fact that when-

40 the roll *i* is so loosely supported that whenever feeding ceases and the gravity rolls 84, 85, tend to pull the web back, the roll *i* instantaneously resists any backward movement of the web because of the friction of its rear surface against the flat face or plate *c* of the

45 fixed bracket. In other words, the roll becomes temporarily wedged between the plate *c* and the web backed by the surface of the drum 83. When feeding is being effected, the movement of the web tends to rotate the 50 roll *i* in the direction of the arrow (Fig. 4) and to somewhat raise the roll so that its presence does not interfere with the feeding.

Among the advantages of the present detent or retainer over such structure as in the 55 Patent No. 1,597,547 are the following:—The roll *i* causes no drag on the paper web when it is being fed, and it will not become flattened in use, and by its occasional rotation it is constantly presenting a fresh surface to bear on the plate *c* and on the paper. The 60 fact that said roll *i* is free to rise and fall and to also rock or tilt endwise (due to the rocking bearing of the cross bar *f* on the stud *e*) enables the roll to act on the paper throughout the length of the roll in conformity with

any unevenness in the surfaces contacting therewith.

The provision of the shoulder *d* enables the detent or retainer to be displaced when desired. For instance, when a web of paper 70 is to be introduced into and threaded through the machine; the roll and yoke are simply pushed up to the position indicated by dotted lines in Figure 4, where they will remain during such installation of the web, and then a 75 slight touch of a finger will dislodge the yoke and roll from such displaced position and they will fall back and automatically resume the operative position of Figure 1.

The Patent No. 1,253,636 hereinbefore referred to is for a bread wrapping machine, but I do not limit myself, so far as the present invention is concerned, to any particular machine which feeds and cuts a paper web, and for this reason I deem it unnecessary to 85 illustrate non-essential parts of any complete machine.

Having now described my invention, I claim:

1. In a machine having means for intermittently feeding a web of paper and cutting it into sections to form wrappers, a rotating support for the web, a fixed plate tangential to said support, and a roll movably supported between said support and plate. 90

2. In a machine of the character described, a support for a web of paper to be fed, a plate adjacent thereto, and a friction roll yieldingly mounted between said support and plate. 100

3. In a machine having means for intermittently feeding a web of paper and cutting it into sections to form wrappers, a rotating support for the web, a fixed plate tangential to said support, and a friction roll between said support and plate, said roll being mounted to be capable of tilting endwise and to move toward and from the narrower portion of the space between said support and plate. 105

4. In a machine of the character described, a support for a web of paper to be fed, a fixed plate adjacent to and spaced from said support, and a friction roll between said support and plate, said roll being mounted to be capable of tilting endwise and to be shifted over said plate. 110

5. In a machine of the character described, a support for a web of paper to be fed, a plate adjacent thereto, and a friction roll yieldingly mounted between said support and plate, means being provided for supporting the roll in temporarily displaced position. 120

6. In a machine of the character described, a support for a web of paper to be fed, a fixed bracket having a flat portion providing a plate adjacent to and spaced from said support, said bracket having a rearwardly projecting stud, a bar supported by said stud 125

130

and having arms, and a roll supported by said arms and bearing against said plate.

7. A paper-retaining attachment for a machine which has a rotating support for a web of paper, said attachment comprising a bracket having a portion which provides a flat face or plate and having a stud behind said face or plate, and a yoke hung upon said stud and carrying a roll extending across said flat face.

10 In testimony whereof I have affixed my signature.
